MICROWAVE KLYSTRON CONSTRUCTION

Gisli C. Dalman, Huntington, N. Y., assignor to Sperry Rand Corporation, a corporation of Delaware

Application August 1, 1956, Serial No. 601,417

16 Claims. (Cl. 315—5.22)

This invention relates to electron discharge devices, and more particularly to output coupling structures for klystrons.

In many klystrons microwave energy is developed in an evacuated cavity resonator. At lower microwave frequencies this energy may be utilized by transmitting it from the resonator to a load through a coaxial line. The coaxial lines and the methods of attaching them to the resonator in vacuum-sealed relationship are mechanically simple and inexpensive. At higher microwave frequencies the energy must be removed from the resonator by means of a waveguide. Because of the relatively large cross-sectional area and the rigidity of the waveguide structure prior art klystrons employing waveguide output assemblies have been mechanically complex and expensive to fabricate.

It is therefore the principal object of this invention to provide an improved coupling structure for an electron discharge device.

It is a further object of this invention to provide an improved waveguide coupling structure for a reflex klystron.

It is a further object of this invention to provide an improved waveguide output structure connected in vacuum sealed relation to the cavity resonator of a reflex klystron.

It is a further object of this invention to provide an improved klystron device that is relatively inexpensive and simple to fabricate and is readily adapted to mass production techniques.

In accordance with the present invention there is provided a reflex klystron having an output waveguide. Energy is transferred from the klystron resonator to the output waveguide by means of a non-resonant intermediate coupling device. The intermediate coupler and the cavity resonator have a common wall, an aperture in the common wall serving to transmit energy from the resonator to the intermediate coupler. An additional aperture in the intermediate coupler provides for energy transfer to the output waveguide. A reflex klystron employing this type of output coupling is simple and inexpensive to fabricate and employs fewer parts than prior art klystrons having waveguide output assemblies.

This invention will be described with reference to the following drawings, wherein:

Fig. 1 is a longitudinal section drawing of a reflex klystron tube employing the structure of this invention;

Fig. 2 is a sectional view of the klystron along the line 2—2 of Fig. 1.

Fig. 3 is a sectional view of the klystron along the line 3—3 of Fig. 1.

Fig. 4 is an exploded view showing the manner of assembly of portions of the klystron of Fig. 1.

The reflex klystron of Figs. 1, 2, 3, 4 comprises a plurality of subassemblies within a cylindrical shell indicated

2

generally as 10. Five major subassemblies are separately fabricated and then joined together to form the klystron. These subassemblies include the lower shell, the cathode, the upper shell, the reflector, and the tuner subassemblies.

5 The lower shell subassembly comprises a lower shell portion 11, which may consist of copper plated cold drawn steel formed into hollow cylindrical form and having a base flange 12 and an end wall 13. End wall 13 is formed with a depression having a cylindrical side wall 14 and a circular bottom wall 15. Bottom wall 15 is provided with an apertured conical reentrant portion 16. A mesh grid 17 is welded to the top edge of reentrant portion 16. A lead wire 18 is inserted in an insulating bushing 19, which in turn is fitted into a hole in end wall 13.

10 The cathode subassembly comprises a cathode button 20, a cylindrical heat shield 21 welded at its upper edge to cathode button 20, and a thin cylindrical foil member 22 affixed to the edge of the heat shield near cathode button 20. Foil member 22 may be formed of thin Kovar, 20 titanium or tantalum to prevent the conduction of heat away from cathode button 20. Cathode button 20 is suitably coated with an electron emissive material. A focus electrode 23 is welded to and supports foil member 22. A heater 24 is disposed inside heat shield 21 and serves to 25 elevate the temperature of cathode button 20. The combination of cathode button 20, heat shield 21, and focus electrode 23 comprises an electron gun. A mica washer 25, provided with holes 26 to aid evacuation, abuts a flange 27 on focus electrode 23. A threaded cylinder 28 30 engages the threaded outer portion of focus electrode 23, forcing mica washer 25 against flange 27. Focus electrode 23 and mica washer 25 are adjusted for concentricity in a jig structure when threaded cylinder 28 is tightened against washer 25.

35 An annular anode member 30 is held against bottom wall 15 by mica washer 25. A gun alignment cylinder 31 has a small flange 32 at its lower edge. Alignment cylinder 31 has substantially the same inner diameter as the outer diameter of cylindrical wall 14 and is provided with 40 slits 33 parallel to the axis of the klystron in order that it may be forced over the outer surface of cylindrical wall 14. Three spring members 34, each affixed at one end thereof to gun alignment cylinder 31, urge said cylinder upward against cylindrical wall 14, whereby the electron gun is held in concentric alignment with the aperture in reentrant portion 16.

The upper shell subassembly comprises an upper shell portion 40, which may consist of cold drawn steel formed into hollow cylindrical form and having a lower lip 41 and an upper flange 42. A rectangular output aperture 43 is provided in the cylindrical surface of upper shell portion 40. A rectangular waveguide section 44 is brazed externally in vacuum-sealed relation to upper shell portion 40 and adapted to surround aperture 43. A waveguide flange 45 is brazed to the outer end of waveguide section 44. A diaphragm retaining ring 46 is brazed to the inner surface of upper shell portion 40 immediately above aperture 43. The entire upper shell subassembly may be silver plated as a unit.

60 Lip 41 of upper shell portion 40 is resistance brazed or welded to end wall 13 of lower shell portion 11 to form a vacuum-tight structure.

The reflector subassembly comprises a reflector sleeve 48 having a lower lip 49. A circular flexible diaphragm 50 having a central apertured portion therein is welded concentrically to lower lip 49. A mesh grid 51 is dis-

posed opposite the apertured portion of diaphragm 50 and is welded between diaphragm 50 and lip 49. A reflector electrode 52 is supported opposite grid 51 and within sleeve 48 by a mica washer 53.

A reflector lead 54 is connected to reflector electrode 52 and projects from sleeve 48 through a slot 55 in sleeve 48. An insulator 56 in slot 55 prevents electrical contact between reflector lead 54 and sleeve 48. An inner screw member 57 having an enlarged base portion 58 is held within sleeve 48, by projections 59 of sleeve 48 engaging a groove 60 of base portion 58. Base portion 58 in turn holds mica washer 53 and consequently reflector electrode 52 rigidly within sleeve 48. The reflector subassembly is affixed to end wall 13 by welding thereto the outer peripheral edges of diaphragm 50. Diaphragm 50, cylindrical wall 14, and bottom wall 15 with its reentrant portion 16 define the walls of a cavity resonator 61. Reflector lead 54 is welded to the end of lead wire 18.

A flexible vacuum diaphragm 63 is brazed in a vacuum-tight manner at its inner periphery to sleeve 48 and at its outer periphery to diaphragm retaining ring 46.

A tuner stop member 65 is adjusted on inner screw member 57, so that at the maximum desirable inward penetration of screw member 57, stop member 65 abuts against flange 42. The tuner subassembly comprises an outer screw member 66, a spring 67 and a tuner cap 68. Outer screw member 66 is threadedly engaged with inner screw member 57 and an inner threaded portion of tuner cap 68. The combination of tuner cap 68, outer screw member 66 and inner screw member 57 comprises a differential screw tuner. Tuner cap 68 is soldered to flange 42 thereby fixing the tuner subassembly with respect to shell 10.

After most of the tube has been assembled in the order heretofore described, a mica vacuum window 70 is hand-glassed to waveguide flange 45.

A metallic header member 72 is welded to the base flange 12 of lower shell portion 11. Header portion 72 contains a plurality of glass eyelets 73 through which pass electrical leads, not shown, to the heater cathode, the anode, the reflector, etc. Also affixed to header 72 are three metallic eyelets 74. The lower ends of spring members 34 are held in place in eyelets 74. An octal base 75 completes the lower portion of the tube assembly.

In operation the electron gun projects a stream of electrons through apertured anode member 30 and across the interelectrode gap defined by grids 17 and 51. The electron stream is reflected by reflector electrode 52 and returns through the interelectrode gap. In a manner well known in the art, electromagnetic oscillations are set up in cavity resonator 61 at the resonant frequency thereof. By adjustment of tuner screw 66, which raises or lowers screw member 57, the spacing between grids 17 and 51 is varied, and, thus, the resonant frequency of cavity 61 is controlled. Base portion 58 of inner screw member 57 provides a conductive short across the end of reflector sleeve 48 thereby preventing any leakage of electromagnetic energy past reflector electrode 52.

In accordance with the principles of this invention, novel means is provided for removing the electromagnetic energy from cavity resonator 61 and transferring it to waveguide section 44 where it may be delivered to a load. Flexible diaphragm 50 includes an additional aperture 78 outside sleeve 48. Aperture 78 is shown as being crescent in shape, but it is within the spirit of this invention for it to be any suitable form. Vacuum diaphragm 63, flexible diaphragm 50, reflector sleeve 48, upper shell portion 40 and end wall 13, define the walls of an intermediate coupler 80. Electromagnetic energy is transferred from cavity resonator 61, through aperture 78 and into intermediate coupler 80. Intermediate coupler 80 resembles in shape a section of coaxial transmission line. In the design of the intermediate coupler, it is desirable that vacuum diaphragm 63 be located sufficiently close

to flexible diaphragm 50 so that the length of the resulting coaxial line section is less than one-half wavelength at the highest operating frequency desired. This prevents the coaxial line section from acting as a resonant cavity of low Q, and reducing the output power. Energy is transferred from intermediate coupler 80, through output aperture 43, into waveguide section 44, where it may be delivered to a load.

While the invention has been described in its preferred embodiment, it is to be understood that the words which have been used are words of description rather than of limitation and that changes within the purview of the appended claims may be made without departing from the true scope and spirit of the invention in its broader aspects.

What is claimed is:

1. An output coupling structure for a reflex klystron comprising a conductive enclosing vessel having a flexible wall portion, a cavity resonator fixedly mounted within said vessel and having a flexible wall portion, said resonator flexible wall portion being provided with a first aperture and being disposed opposite said vessel flexible wall portion, a rigid hollow conductive tube affixed at each end thereof to a respective one of said flexible wall portions, the end of said tube affixed to said resonator flexible wall portion being adapted to surround said first aperture, an electron reflecting electrode insulatingly supported within said tube, said resonator flexible wall portion being further provided with a second aperture outside said tube, whereby said second aperture serves to transfer electromagnetic energy from said cavity resonator to an intermediate coupler, said enclosing vessel, said enclosing vessel flexible wall portion, said tube, and said resonator flexible wall portion defining in part the walls of said intermediate coupler, and further coupling means for removing electromagnetic energy from said intermediate coupler.

2. An output coupling structure for a reflex klystron comprising a conductive cylindrical shell, a flexible wall extending across the interior of said shell in vacuum sealed relation to the inner surface thereof, a hollow annular cavity resonator coaxially disposed within said shell, one wall of said resonator being provided with a flexible portion, said flexible portion being provided with a central circular first aperture and being disposed opposite said flexible wall, an annular disc extending between the outer circular surface of said resonator and the inner surface of said shell and rigidly supporting said resonator within said shell, a rigid hollow conductive tube affixed at one end thereof to said flexible wall and at the other end thereof to said flexible portion, the end of said tube affixed to said flexible portion being of greater inside diameter than the diameter of said first aperture and being adapted to surround said first aperture, and an electron reflecting electrode insulatingly supported within said tube, said one resonator wall being further provided with a second aperture outside said tube, whereby said second aperture serves to transfer electromagnetic energy from said cavity resonator to an intermediate coupler, said shell, said flexible wall, said one resonator wall, said annular disc, and said tube defining in part the walls of said intermediate coupler, said cylindrical shell being provided with a third aperture between said flexible wall and said annular disc whereby electromagnetic energy may be removed from said intermediate coupler.

3. An output coupling structure, as in claim 2, further including a conductive member, said member being adapted to enclose said tube at said one end thereof, whereby leakage of electromagnetic energy through said tube is prevented.

4. A reflex klystron comprising a conductive enclosing vessel having a flexible wall portion, a cavity resonator mounted within said vessel and having a pair of opposed walls, one of said resonator walls being provided with a

flexible portion, said flexible portion being provided with a first aperture and being disposed opposite said vessel flexible wall portion, the other of said resonator walls being provided with a second aperture aligned with said first aperture, an electron gun aligned with said first and second apertures and opposite said other resonator wall for projecting an electron stream through said first and second apertures for interaction with said resonator, a rigid hollow conductive tube affixed at each end thereof to a respective one of said flexible wall portions, the one end of said tube affixed to said resonator flexible wall portion being adapted to surround said first aperture, an electron reflecting electrode insulatingly supported within said tube, said resonator flexible wall portion being provided with a third aperture outside said tube, whereby said third aperture serves to transfer electromagnetic energy from said cavity resonator to an intermediate coupler, said enclosing vessel, said enclosing vessel flexible wall portion, said tube, said one resonator wall, and said resonator flexible wall portion defining in part the walls of said intermediate coupler, and further coupling means for removing electromagnetic energy from said intermediate coupler.

5. A reflex klystron as in claim 4, further including tuning means mounted on said enclosing vessel and connected to said tube for varying the longitudinal position thereof and thereby changing the resonant frequency of the cavity resonator.

6. A reflex klystron as in claim 4, further including a conductive member, said member being adapted to enclose said tube at the other end thereof, whereby leakage of electromagnetic energy through said tube is prevented, a portion of said conductive member extending beyond said tube and having screw threads thereon, and tuning means mounted on said enclosing vessel and engaging said conductive member screw threads for varying the longitudinal position of said tube.

7. An output coupling structure for an electron discharge tube comprising a cylindrical conductive shell, a first flexible conductive wall extending across the interior of said shell in vacuum sealed relation to the inner surface thereof, a second flexible conductive wall extending across said shell opposite said first wall, a rigid rod affixed at each end thereof to a respective one of said flexible walls, said second wall being provided with an aperture, whereby said aperture serves to transfer electromagnetic energy into the hollow structure bounded by said shell and said first and second walls, and further coupling means for removing electromagnetic energy from said hollow structure.

8. An output coupling structure as set forth in claim 7, wherein said further coupling means comprises a rectangular aperture through said cylindrical conductive shell, and a section of rectangular wave guide having an end coupled to said aperture.

9. In a velocity modulation device a subassembly comprising a hollow conductive member having an integral end wall, said end wall being provided with a depression having a cylindrical side wall and a circular bottom wall, said bottom wall being provided with a circular aperture concentrically located therein, an alignment cylinder having an internal diameter substantially equal to the external diameter of said cylindrical wall, an electron gun rigidly connected to said alignment cylinder and coaxial therewith, the electron emitting surface of said gun facing said aperture, and spring means fixed at one end with respect to said hollow member and connected at the other end to said alignment cylinder whereby one end of said alignment cylinder is urged against the cylindrical wall, thereby maintaining the electron gun coaxial with said aperture.

10. A subassembly for a velocity modulation tube as in claim 9, further including a circular flexible member, said member having a greater diameter than that of said cylindrical wall, said flexible member being disposed coaxially within said cylindrical wall and being fixed about

its outer periphery to said end wall, whereby a cavity resonator is defined by said depression walls and said circular flexible member.

11. In a velocity modulation device a subassembly comprising a hollow conductive member having an integral end wall, said end wall being provided with a depression having a cylindrical side wall and a circular bottom wall, said bottom wall being provided with a circular aperture concentrically located therein, an alignment cylinder, and an electron gun rigidly connected to said alignment cylinder and coaxial therewith, the electron emitting surface of said gun facing said aperture, said alignment cylinder being disposed to surround said cylindrical wall and to fit tightly over said cylindrical wall, thereby maintaining the electron gun coaxial with said aperture.

12. An output coupling structure for reflex klystrons comprising a conductive cylindrical shell, a hollow annular cavity resonator concentrically disposed within said shell, one wall of said resonator being provided with a flexible portion, said flexible portion being provided with a central circular first aperture, said resonator being rigidly supported within said shell by an annular disc extending

20 between the outer circular surface of said resonator and the inner surface of said shell, a rigid hollow conductive tube affixed at one end thereof to said flexible portion, said tube end being of greater inside diameter than the diameter of said first aperture and being adapted to surround said first aperture, a conductive flexible annulus extending between the outer surface of said tube and the inner surface of said shell in vacuum-sealed relation thereto, and an electron reflecting electrode insulatingly supported within said tube, said one resonator wall being further provided with a second aperture outside said tube, whereby said second aperture serves to transfer electromagnetic energy from said cavity resonator to an intermediate coupler, said shell, said flexible annulus, said one resonator wall, said annular disc, and said tube defining in part the walls of said intermediate coupler, said cylindrical shell being provided with a third aperture between said flexible annulus and said annular disc, whereby electromagnetic energy may be removed from said intermediate coupler.

25 13. An output coupling structure as in claim 12, further including a section of rectangular waveguide affixed to the outer surface of said shell in vacuum-sealed relation thereto and adapted to surround said third aperture, and a dielectric window member extending across said waveguide section and sealed to the walls thereof.

30 14. A coupling structure as in claim 12 wherein the distance between said flexible portion and said flexible annulus as measured along the axis of said cylindrical shell is less than one-half wavelength at the maximum frequency of the electromagnetic energy to be transferred through said intermediate coupler.

35 15. An output coupling structure as in claim 12 wherein said hollow conductive tube is provided with an aperture in the wall thereof between said flexible wall and said flexible portion, and wherein said annular disc is provided with an aperture, and further comprising a conductive lead connected to said reflecting electrode, said conductive lead extending through said tube aperture, said intermediate coupler, and said annular disc aperture.

40 16. A reflex klystron subassembly comprising a hollow conductive member having an integral end wall, said end wall being provided with a depression having a side wall and a bottom wall, a flexible member provided with an aperture and affixed to said end wall to cover said depression, a first hollow conductive tube affixed to said flexible member and surrounding the flexible member

45 aperture, a reflector electrode insulatingly supported within said first tube, said first tube being provided with an aperture through the wall thereof, said end wall being provided with an aperture outside said depression, a conductive lead connected to said reflector electrode and ex-
